(57) **CLAIM**

The ornamental design for a trampoline shade cover, as shown and described.

DESCRIPTION

FIG. 1 is a top view of a trampoline shade cover showing my new design;

FIG. 2 is a bottom view thereof;

FIG. 3 is a side view thereof;

FIG. 4 is a front view thereof; and,

FIG. 5 is a perspective view thereof.

The broken line showing of the trampoline shade cover is for the purpose of illustration portions of the article and forms no part of the claimed design.

1 Claim, 5 Drawing Sheets
